UNITED STATES PATENT OFFICE

2,532,657

HANDLE FOR MATTRESSES AND THE LIKE

Michael Bechik, St. Paul, Minn., assignor to
Bechik Products, Inc., St. Paul, Minn., a corpora-
tion of Minnesota

Application September 24, 1949, Serial No. 117,633

1 Claim. (Cl. 5—345)

1

My invention relates to an improvement in handles for mattresses and the like, and, generally stated, consists of the novel devices, arrangement of devices, and novel arrangement or parts hereinafter described and defined in the claim.

Referring to the drawings, wherein like characters indicate like parts throughout the several views:

Fig. 1 is a fragmentary view of a mattress illustrating my novel handle construction secured to the side wall thereof; and

Fig. 2 is an enlarged fragmentary view, partly in plan and partly in section, taken on the line 2—2 of Fig. 1.

Referring with greater particularity to the drawings, the numeral 1 indicates in its entirety a mattress having a side wall 2 formed of conventional boxing. Shown as secured to the wall 2 in spaced relation to each other are a pair of grommets 3, which are peened on their inner ends against washers 4 so as to securely lock the washers in place against the inner surface 5 of the member 2.

An elongated handle 6, preferably formed from cord or the like, is shown as lying flush against the outer surface 7 of the wall 2 with its free ends 8 projecting one each through one of the grommets 3. Adjacent the free ends 8, said handle member 6 is provided with anchoring heads 9, which are of a size and shape to normally discourage passage outwardly thereof through the grommets 3. Particularly, and as shown, the anchoring heads 9 are of the type disclosed in my earlier Patent No. 2,248,328. However, for the purpose of this invention, it is specifically understood that said anchoring heads 9 may vary considerably in size and shape. It will be noted that the length of the handle 6, intermediate the anchoring head 9, is somewhat greater than the distance between the grommets 3 when the mattress wall 2 is stretched taut. Therefore, the portion of the handle member 6 along the outer surface 7 of the wall 2 would normally tend to drop down or sag in view of this slack. To obviate this, I interpose a coil compression spring 10 intermediate one of the washers 4 and its adjacent or cooperating head

2

9. It will be observed that said coil compression spring has sufficient strength to stretch the handle 6 taut against the outer surface 7 of the wall 2 when the handle is not being used. On the other hand, when a hand is inserted between the handle 6 and the wall 2, the spring will be compressed sufficiently to readily accommodate the hand and without stretching of the side wall.

My invention has been thoroughly tested and 10 found to be completely satisfactory for the accomplishment of the above objects, and while I have disclosed a commercial form of my invention, it should be understood that same is capable of modification without departure from 15 the scope of the appended claim.

What I claim is:

In combination with a mattress wall, a pair 20 of washers, a pair of grommets extending through said mattress wall and said washers in spaced relation and securing the latter to the inside wall of the former, a flexible handle extending along the outer surface of said wall with its free ends projecting one each through one of said grommets, anchoring heads on the opposite ends 25 of said handle within said wall, said heads normally being incapable of passing outwardly through said grommets and being longitudinally-spaced on said handle a distance greater than the distance between said grommets, and a coil 30 compression spring interposed between one of said heads and the adjacent grommet on the inside of said mattress wall whereby to stretch the handle intermediate said grommets taut along the exterior of said mattress wall.

MICHAEL BECHIK.
